Primary Examiner—A. Hugo Word*Assistant Examiner*—Doris Clark*Attorney, Agent, or Firm*—Ralph W. Selitto, Jr.[57] **CLAIM**

The ornamental design for a bracket for a tree climber, as shown and described.

DESCRIPTION

FIG. 1 is a front perspective view of a bracket for a tree climber showing my new design;
 FIG. 2 is a front elevational view thereof;
 FIG. 3 is a rear elevational view thereof;
 FIG. 4 is a right side elevational view, the left side being a mirror image thereof;
 FIG. 5 is a top plan view thereof; and,
 FIG. 6 is a bottom plan view thereof.

FIG. 1

FIG. 2

FIG. 3

FIG. 4

FIG. 5

FIG. 6
